United States Patent Office.

LEFFERT R. CORNELL, OF FLATBUSH, NEW YORK.

Letters Patent No. 69,411, dated October 1, 1867.

IMPROVEMENT IN STEAM SUPERHEATERS.

The Schedule referred to in these Letters Patent and making part of the same.

TO ALL WHOM IT MAY CONCERN:

Be it known that I, LEFFERT R. CORNELL, of Flatbush, Kings county, New York, have invented a new and improved "Superheater;" and I do hereby declare that the following is a full, clear, and exact description thereof, which will enable others skilled in the art to make and use the same, reference being had to the accompanying drawings, forming part of this specification.

The present invention consists in a novel construction and arrangement of pipes and tubes for the conduction and passage of steam for the superheating of the same, the principle of which construction consists in providing barriers to the passage of the steam, and in so running the pipes or tubes that the steam will be made at points of its passage through the superheater to strike against the sides or surfaces thereof, and thus have its particles so broken or separated as to be the more fully and perfectly subjected to the action of the heated currents circulating about or surrounding the superheater. In the accompanying plate of drawings my improvement in superheaters is illustrated—

Figure 1 being a plan or top view of the same.

Figure 2, an end view or elevation.

Figure 3, a horizontal longitudinal section taken in the plane of the line $x\ x$, fig. 2.

Figure 4, a vertical longitudinal section taken in the plane of the line $y\ y$, fig. 1.

Figure 5, a transverse vertical section taken in the plane of the line $z\ z$, fig. 4.

Similar letters of reference indicate corresponding parts.

A A, in the drawings, represent two similar cylinders or drums, placed one alongside of the other, but at a short distance apart, and parallel to each other, and with each cylinder supported in a horizontal position, or nearly so, by means of uprights, A², at suitable points. In these cylinders, at different points of their length, and at equal distances apart, or nearly so, is a series of cross-heads or partitions, B, dividing the cylinders into a series of chambers or spaces, B². C, a series of pipes or tubes, connecting the two cylinders A together. These pipes C extend upward from the cylinders, in an arched or curved shape, opening at each end in the upper side thereof, and are so arranged as to form a continuous communication between the several chambers of the cylinders, from one end to the other. E, pipes, running along the under side of the cylinders, from one end to the other, with the several chambers of which cylinders the pipes E communicate through short connecting pipes D. At one end of one of the cylinders A the steam is admitted, which, passing into the same, strikes against its first partition, and escapes up through the first arched pipe C into the first chamber of the next cylinder, against the side of which it strikes, owing to the downward direction of the tube, and from thence passes through the next pipe C, striking in its passage thereto against the first partition of the said second cylinder into the second chamber of the first cylinder, against the sides of which it impinges, and so on; through the third pipe to the second cylinder, and from thence back again to the first cylinder, and so on, until it reaches the end of the cylinders, when it there escapes through any suitable outlet provided for it; the steam as it is passing through the cylinders, as above described, being subjected to the action of heat, which causes it to become superheated to a greater or less extent, and according to the degree of heat employed, as is obvious. But, by the peculiar manner in which the steam passes through the superheater, it is, as it were, broken up or separated, and consequently the more perfectly subjected to the action of the heat employed to superheat it, economizing not only in the heat necessary in a corresponding degree, but at the same time enabling the steam to be so superheated as to be, as it were, perfectly dry. Through the pipes E the condensed steam or water, if any, escaping from the cylinders can be drawn off when so desired.

Having thus described my invention, what I claim as new, and desire to secure by Letters Patent, is—

The superheater, constructed as described, consisting of the parallel cylinders A divided into chambers B² by heads B, and supported by means of the uprights A², said chambers connected alternately by means of the curved pipes C, and connecting with the parallel condensing pipes E beneath each cylinder by means of the short pipes D, as herein shown and set forth for the purpose specified.

The above specification of my invention signed by me this   day of April, 1867.

LEFFERT R. CORNELL.
